DOOR LOCK

Harry E. Fendring, Los Angeles, Calif., assignor,
by mesne assignments, to California Lock Company,
Los Angeles County, Calif., a corporation
of California

Application January 27, 1939, Serial No. 253,132

19 Claims. (Cl. 70—153)

My invention relates to door locks, portions thereof being applicable to door latches.

One of the principal objects of this invention is to provide a door lock which is very simple and economical to manufacture, proportionate to its functions, and which has relatively few parts compared with other locks and latches.

Another very important object of this invention is to provide a lock of this class which requires a minimum of effort, time, and skill to install or to remove, and thereby reducing installation costs to a minimum.

Another important object of this invention is to provide a simple and novel template for marking the door preparatory to installation, and one which is simple to use, thereby further reducing installation costs, and also the elements of error.

Another very important object of this invention is to provide a lock of this class having, what may be known as, a floating spindle, which may be readily actuated for performing different functions.

Still another important object is to provide a lock which may be readily reversed so that the lock may be used at either edge of door, or the specific knobs placed on either side of the door.

Another important object of this invention is to provide a novel and simple dead-lock attachment, or burglar-proof lock.

An important object also is the provision of a lock having relatively few screws.

A further object of this invention is to provide a door lock of this class which will not readily deteriorate or get out of order.

With these and other objects in view, as will appear hereinafter, I have devised a door lock having certain novel features of construction, combination, and arrangement of parts and portions, as will be hereinafter described in detail, and particularly set forth in the appended claims, reference being had to the accompanying drawings and to the characters of reference thereon, which form a part of this application, in which:

Fig. 1 is a transverse section of the free edge of a door, showing my door lock, in one form, mounted thereon, portions of my lock being broken away and in section to facilitate the illustration, and other parts being shown by dotted lines when shifted;

Fig. 2 is a longitudinal sectional view thereof, with the section taken at 2—2 of Fig. 1, and showing a key in the lock thereof;

Fig. 3 is a fragmentary view of the outer end of the spindle;

Figs. 4, 5, and 6 are transverse sectional views

thereof, taken respectively at 4—4, 5—5, and 6—6 of Fig. 2;

Fig. 7 is a sectional view taken at 7—7 of Fig. 4, showing the spindle locking means;

Fig. 8 is a longitudinal sectional view of a modified construction of my door latch incorporating features of my invention;

Fig. 9 is a perspective view of a modified construction of the bolt-retracting and stop means; and,

Fig. 10 is a perspective view of the template for marking the door to facilitate installation.

The lock, shown in the drawings, is embodied in a conventional door, designated A, and is provided with a usual bolt or latch mechanism B, and the operating mechanisms C and D for operating the door lock from the inside and outside of the door.

A large transverse hole A¹ is drilled near the free edge of the door, and a smaller hole A² is drilled into the edge of the door at right angles to the former, and with the axis of the hole A² intersecting the axis of the hole A¹. In Fig. 10 is shown a template E which fits over the edge of the door and is provided with small holes E¹ and E² for marking the centers for drilling the holes A¹ and A².

At the opposite sides of the door A are positioned discs 1 and 2. They are located with respect to the holes by a plurality of flanges or flat lugs 1^a and 2^a which engage the cylindrical wall of the hole A¹. These plates are temporarily secured in position, (that is, by pressing the same with the fingers) by spurs 1^b and 2^b which extend in the same direction as the flanges, but are shorter than said flanges and are positioned radially outwardly therefrom. The circumferential positions of the discs are determined by marks 1^c and 2^c which are aligned with marks on the door made by means of notches E³ on the template. These plates are secured together by bolts which consist preferably of studs 2^d, which may be integrally secured to the outside plate, and nuts 1^d screwed on the studs through the disc 1. In these plates are rotatably mounted knobs 3 and 4, respectively. These knobs may be retained in position by pins or studs 5 and 6. The discs 1 and 2 may be concealed by ornamental escutcheon plates or covers 7 and 8 which may be merely snapped over the peripheral edges of the discs. For this purpose the peripheral edges of the discs are inwardly bevelled and the escutcheon plates are provided with similarly inclined peripheral flanges. These ornamental escutcheon plates may be omitted and the discs

50 45 40 35 30 25 20 15 10 5 55

1 and 2 serve as the escutcheon plates for the lock.

A square spindle 9 extends axially into the knobs, is axially shiftable relative thereto, and rotatable with both. The outer end 9^a of the spindle is reduced and is threaded at its end. To this threaded end is secured a plug or button 10. Around this end of the spindle, and between the button 10 and shoulder 3^a of the knob 3, is a compression spring 11, which tends to force the spindle inwardly with respect to the door, that is, outwardly with respect to the knob 3. This is the locking position, and is shown by dotted lines in Figs. 1 and 2.

In the knob 3 is a transverse slot 3^b in which is mounted a yoke 12 which straddles the spindle and is adapted to enter a notch 9^b in the spindle when the latter is shifted to its open or unlocked position by the button 10. A compression spring 13 is adapted to cause the yoke 12 to enter the notch 9^b. The yoke may be unseated by a button 12^a at the underside of the knob, and allow the spring 11 to force the button 10 beyond the knob 3, that is, force the spindle to its locking position.

In the knob 4 is mounted a conventional cylinder lock consisting of a cylinder barrel 21 and a cylinder plug 22 which receives a key F from the outer end of the cylinder lock. The cylinder barrel of my cylinder lock has an outer annular flange 21^a which forms the outer contour of the central portion of the knob. This cylinder barrel is secured in position in the knob by means of screws 23 from the inner end of the knob. The cylinder plug 22 has an axially extending tubular portion 22^a into which a cylindrical portion 24 at the outer end of the spindle 9 extends. This cylindrical portion 24 is provided with helical cam grooves 24^a into which diametrically opposed lugs 22^b, at the inner end of the tubular portion 22^a, extend. Thus, when the cylinder plug 22 is rotated, the lugs 22^b ride in the helical cam grooves and cause the spindle to move longitudinally. In this instance, if the key F is rotated clockwise, the spindle 9 is drawn outwardly, that is, against the action of the spring 11.

The latch unit B of my lock consists of a housing 31, a bolt 32, a spring 33, a link 34, and an operating arm 35.

The housing 31 has an enlarged outer end 31^a, which is tapered inwardly from its outer face, and an inner portion 31^b of square cross-section, the latter portion having a longitudinal opening 31^c of square cross-section. In this longitudinal opening is reciprocally mounted the bolt 32 which, at the outer end, is square and is of a size to slide freely in the opening.

I have made the outer end of the latch housing slightly tapered so that the same may be merely forced into the drilled hole A², and frictionally retained therein without other securing means.

In the template E is provided a slit E⁴ whereby a mark is made on the edge of the door so that a corresponding mark 31^d on the latch housing may be aligned therewith, and the latch housing, thus, properly secured in position.

The outer end of the bolt has a bevelled or curved end 32^a, as in the usual construction. The inner or flat side of the bolt, in contradistinction to the cut-a-way side, has a narrow plate portion 32^b, which extends the full length of the bolt and projects through an opening 31^d at the inner end of the housing. The bolt has

a step portion 32^c between the large outer end 32^a and the narrow inwardly extending end 32^b, in which one leg of the U-shaped wire link 34 is pivotally mounted. The cross-portion of this link is positioned in the rectangularly shaped opening 31^c and extends beyond the rear wall of the latch housing. Between the step portion 32^c of the bolt and the rear wall of the housing is positioned the compression spring 33. The link 34 is connected to the portion 32^c by forcing the bolt 32 inwardly, and then inserting the cross portion or outer leg of the link through a slot 31^e at the side of the housing and into the registering opening in step 32^c, as shown in Figs. 1 and 6.

The other or inner leg 34^a of the link extends through a radial slot 35^a in the bolt operating member or arm 35, which is secured, by a pin, to, and extends radially from the spindle 9.

Spaced from the arm 35, that is, with respect to the axis of the spindle 9, is a stop 36, which is joined with the arm 35, at the opposite sides of the slot 35^a, by walls 36^a. When the spindle is forced in its outward or open position against the compression of the spring 11, and latched by yoke 12, the bolt 32 may be freely forced inwardly with the inner end of the link moving in the radial slot of the arm 35. But when the spindle is released by the latch 12 and allowed to be forced longitudinally by the spring 11, the stop 36 is shifted into the dotted line position, shown in Fig. 1, in alignment with the link 34, and is thereby prevented from being forced inwardly. Thus, the bolt 32 cannot be pried inwardly unless a key F is used or the button 10 forced into the knob 3.

The arm 35 and stop 36 extend preferably in diametrically opposite directions so that the lock may be used on either edge or either side of a door.

Around the portion of the hub of the knob 4, which extends inwardly from the escutcheon plate or disc 2, is a flexible coil spring 41 which has hooks 41^a and 41^b at its ends. These hooks are hooked around the stud or projection 6, carried by the hub of the knob 4, and a pin 42 secured to the inner side of the disc or plate 2, all as shown best in Figs. 1, 2, and 5. As one of the knobs 3 or 4 is rotated in either direction, one of the hooks is held stationary by the pin 42 and the other hook is carried by the stud 6, exerting a tension on the spring, which spring in turn tends to return the knobs to a neutral position, as shown in Fig. 5. The end of the stud 6 is T-shaped so as to facilitate the retention of the spring 41 in position.

On the inner side of the disc or plate 1 is an arcuate flange 51, which provides a widened bearing for the inner end of the hub of the knob 3. At the upper side of the hub is located the pin 5, above referred to, which engages the ends of the flange 51 for limiting the rotation of the knobs and spindle in opposite directions from the aforementioned neutral position. The spindle 9 carries a long pin 53 which, when the spindle is shifted and latched by the latch 12, is clear of the flange 51, but when the spindle is released by the latch, the pin 53 engages the inner edge of the flange. This flange is provided with a shallow notch 51^a and a deeper notch 51^b, as shown best in Fig. 7. The spring 41 holds the spindle and pin 53 in a neutral position, and when the spindle is released by the latch 12, the pin 53 enters the notch 51^a, locking the spindle against rotation in one direction, and thereby

preventing withdrawal of the bolt 32 by either knob. After the spindle is rotated in the opposite direction, the pin 53 is forced into the notch 51^b by the spring 11, which prevents rotation of the spindle in either direction, and prevents absolutely the inward movement of the bolt 32, by reason of the stop 36 being positioned in alignment with the link 34. The bolt is thus locked while the pin 53 is in the notch 51^b, unless, of course, the button 10 is depressed or the keys inserted and rotated. This also provides a burglar-proof lock, so that a flat instrument may not be placed between the door jamb and the door for prying the bolt inwardly.

It will be noted that if the arm 35 is secured to the spindle 9 in the dot and dash lines position, designated G in Fig. 6, the bolt and link will be in a dead center position with respect to the stop 36 and the spindle 9, when the pin falls in the notch 51^b, thus, rendering the forcing of the bolt 32 inwardly still more difficult.

In Fig. 9 of the drawings, I have shown a modified construction of the bolt actuating arm 35 and the link 34 which connects the bolt to the arm. In this modification the stop member or lever 36 is eliminated, and the arm and link modified instead. This modification consists of a flattened portion 34^a on the round portion or leg 34^c at the free end of the wire link, and a modified slot 35^a on the arm. This modified slot is narrow but sufficiently wide to receive only the flattened portion 34^b of the link. The outer end of the slot is enlarged or provided with an enlarged cylindrical end 35^b for receiving the round portion 34^c at the end of the leg 34^a of the link. When the spindle 9 is in an open or unlocked position, the arm 35 is in alignment with the flattened portion 34^b so as to permit the bolt 32 to be freely moved inwardly from this outer end, but this portion of the arm also permits said arm to be freely rotated for withdrawing the bolt. When the spindle is shifted to its locking position, as shown in Fig. 9, the rounded portion 34^c is positioned in the enlarged cylindrical hole 35^b which prevents the link from being forced inwardly, thus, forming a burglar-proof, or dead-lock, as described above.

When the button 10 is depressed, as shown in Figs. 1 and 2, the lock is open, that is, unlocked, and serves merely as a latch, whereby the bolt may be readily forced inwardly by the strike plate or the door jamb, and withdrawn or retracted by either knob when desiring to open the door. When desiring to lock the door, which can only be done from the inside, and when the door is either open or closed, the latch 12 is raised, allowing the spring 11, when the spindle is in the central or neutral position, as shown, to force the pin 53 into the notch 51^a. This prevents rotation of the knobs in one direction. As soon as one of the knobs is rotated in the opposite direction, the pin 53 falls into the notch 51^b, which prevents either knob from turning, and also causes the stop 36 to shift into alignment with the link 34 and thereby prevent the bolt from being forced inwardly. The lock may again be opened by pressing the button 10 inwardly, or by turning the key F in a clockwise direction, which causes the lugs 22^b to engage the helical cam 24^a and draws the spindle in the same direction as when depressing the button.

It will be noted that the cylindrical portion 24 of the spindle has longitudinal grooves 24^b which permits the spindle to be freely longitudinally shifted by the button 10 or spring 11.

It will be also noted that the cylindrical member 24 also has longitudinal walls 24^c at the inner ends of the helical cams to prevent complete rotation of the cylinder plug or key.

5 The device shown may be used as a bedroom or other room latch, without the lock in the knob 4. In this instance, the knob 3 with its button 10 and latch 12 is placed on the room side of the door which is to be locked.

10 If it is desired to use the structure shown as a bathroom latch, ordinances often require the provision of means for unlocking the door from the outside. To meet this requirement, I have provided a pin 61 at the underside of the outside knob, as shown in Fig. 8, which permits the bolt to be drawn in the same direction as the depressing of the button 10, and thereby unlocking the structure.

15 When the lock is used as a room latch, the pin and notch means may consist merely of a pin 53 and one notch 51^b, so that when the spring 11 is released by the latch 12, the pin 53 is carried directly into the notch 51^b.

20 Though I have shown and described a particular construction, combination and arrangement of parts and portions, and certain modifications thereof, and have referred particularly to locks, I do not wish to be limited to the same but desire to include in the scope of my invention, the construction, combination, and arrangement, substantially as set forth in the appended claims, whether applied to locks, latches, or analogous devices.

I claim:

25 1. In a door lock, a housing, operating members rotatably mounted on but axially fixed at the opposite sides of the housing, a spindle rotatably mounted in the housing and axially reciprocable with respect to the operating members, a bolt reciprocally mounted at right angles to the spindle, means on the spindle for retracting the bolt and to allow free reciprocation of the bolt when the spindle is in one position, stop means in connection with the bolt retracting means and axially shiftable with the spindle to prevent free reciprocation of the bolt when the spindle is axially shifted from said position, and means for positively retaining the spindle in the latter position.

30 2. In a door lock, a housing, a spindle rotatably mounted and axially reciprocable in the housing, a bolt reciprocally mounted at right angles to the spindle, a slotted arm on the spindle, a pivoted link extending from the bolt into the slot of the arm for retracting the bolt, said slot allowing free inward movement of the bolt when the spindle is in one position, a stop on the spindle adapted to be shifted by the spindle in alignment with the link to prevent such inward movement of the bolt, and means for retaining the spindle in said shifted position.

35 3. In a door lock, a housing, a spindle rotatably mounted and axially reciprocable in the housing, a bolt reciprocally mounted at right angles to the spindle, a slotted arm on the spindle, a pivoted link extending from the bolt into the slot of the arm for retracting the bolt, said slot allowing free inward movement of the bolt when the spindle is in one position, said arm having a stop spaced from the slotted portion, said stop being adapted to be shifted by the spindle and with the arm in alignment with the link to prevent such inward movement of the bolt, and means for retaining the spindle in said shifted position.

4. In a door lock, a housing, a spindle rotatably mounted and axially reciprocable in the housing, a bolt reciprocally mounted at right angles to the spindle, means on the spindle for retracting the bolt and to allow free reciprocation of the bolt when the spindle is in unlocked position, a pin and notch means associated with the spindle, a spring normally urging the pin to enter the notch of the pin and notch means for locking the spindle, means for manually moving the spindle against the action of the spring, and a latch for latching the spindle in an unlocked position when shifted by said manual means for holding the pin out of the notch.

5. In a door lock, a housing, a spindle rotatably mounted and axially reciprocable in the housing, a bolt reciprocally mounted at right angles to the spindle, means on the spindle for retracting the bolt and to allow free reciprocation of the bolt when the spindle is in unlocked position, a pin and a notch means associated with the spindle, a spring normally urging the pin to enter the notch of the pin and the notch means for locking the spindle, means at one end of the spindle for manually moving the spindle against the action of the spring, a helical cam on the opposite end of the spindle, and a cylinder lock having a cylinder plug for engaging the helical cam and shifting the spindle in the same direction as said manual means.

6. In a door lock, a pair of spaced axially aligned plates, a pair of door knobs axially aligned and rotatably mounted on said plates, a spindle axially aligned and rotatable with both knobs, but shiftable longitudinally with respect thereto, a bolt, means connecting the spindle to the bolt for causing retraction thereof when the spindle is in an unlocked position, stop means in connection with the spindle to prevent free reciprocation of the bolt, a spring for normally forcing the spindle into a locking position and for shifting the stop means into a position to prevent the reciprocation of the bolt, a manual means in one of said knobs for forcing the spindle against the action of the spring, a latch means for latching the spindle in the latter position, and means in the other knob for forcing the spindle in the same direction as said manual means.

7. In a door lock, a housing, a spindle rotatably mounted and axially reciprocable in the housing, a latch member movably mounted at one side of the spindle, an arm on the spindle, said arm having a narrow slot and enlarged opening at the outer end of the slot, a link connected to the latch member and provided at its inner end with a narrow portion adapted to slide in the slot and also provided with an enlarged portion adapted to fit freely in the enlarged opening at the outer end of the slot, means for shifting the spindle longitudinally and said arm in alignment with the narrow portion of the link, means for shifting the spindle into a locking position with the arm in alignment with the enlarged portion of the link to prevent shifting of the latch member, and means to limit the rotation of the spindle.

8. In a door lock, a bolt housing having a longitudinal opening and an abutment at the inner end of the opening, a bolt having a large outer end slidably fitting into said opening and having a plate portion extending backwardly through the rear end of the housing at one side of said abutment, a spring between the large end of the bolt and said abutment, and a substantially

U-shaped link pivotally connected with one leg in the enlarged portion of the bolt and with the other leg extending beyond the inner end of the housing, the portion of the link connecting the legs being positioned within the longitudinal opening of the housing between the spring and the adjacent wall of the housing.

9. In a door lock, a housing, a spindle rotatably mounted and axially reciprocable in the housing, a bolt reciprocally mounted at right angles to the spindle, means on the spindle for retracting the bolt and to allow free reciprocation of the bolt when the spindle is in unlocked position, stop means on and axially shiftable with the spindle to prevent free reciprocation of the bolt when the spindle is axially shifted from said unlocked to a locking position, an actuating member for manually forcing the spindle and stop means from a locking to an unlocked position, a spring positioned for normally forcing the spindle into a locking position and urging the actuating member in opposition to manual operation, and a latch for latching the spindle in an unlocked position when said spring actuated member is manually operated.

10. In a door lock, a housing, a spindle rotatably mounted and axially reciprocable in the housing, a bolt reciprocally mounted at right angles to the spindle, means on the spindle for retracting the bolt and to allow free reciprocation of the bolt when the spindle is in unlocked position, stop means on and axially shiftable with the spindle to prevent free reciprocation of the bolt when the spindle is axially shifted from said unlocked to a locking position, a spring normally forcing the spindle into locking position, a latch for latching the spindle in an unlocked position against the action of said spring, a pin and a notch means in connection with the spindle whereby the pin is forced into a notch of the notch means by the spring when released by the latch, said notch being so shaped as to allow rotation of the spindle in one direction, and another notch in connection with the former notch means for receiving the pin when the spindle is rotated in the latter direction, to thereby shift the stop into operative position.

11. In a door lock, a pair of spaced axially aligned plates, a pair of door knobs axially aligned and rotatably mounted on said plates but axially fixed with respect thereto, a spindle mounted with its ends in both knobs and axially aligned and rotatable therewith, but shiftable longitudinally with respect thereto, a bolt, means connecting the spindle to the bolt for causing retraction thereof when the spindle is in an unlocked position, a spring for normally forcing the spindle into a locking position, and a manual means in one of said knobs for forcing the spindle against the action of the spring.

12. In a door lock, a housing, operating members rotatably mounted but axially secured to the opposite sides of the housing, a spindle mounted with its ends on and rotatable with both of said operating members and axially reciprocable with respect to both, a latch member, and means on the spindle for retracting the latch member.

13. In a door lock, a housing, operating members rotatably mounted on the opposite sides of the housing, an axially shiftable latch operating member in the housing, a latch member, means connecting the latch member to the actuating member for operating the latch member when the actuating member is in unlocked position.

means for axially shifting the actuating member into locking and unlocked positions, a helical cam on one end of the actuating member and in association with one of the operating members, and a lock having a cylinder plug for engaging the helical cam and shifting the actuating member in one direction, said helical cam having a longitudinal passage for allowing the actuating member to be shifted axially in the same direction without the movement of said helical cam.

14. In a door lock, a housing, operating members rotatably mounted on the opposite sides of the housing, an axially shiftable latch operating member in the housing, a latch member, means connecting the latch member to the actuating member for operating the latch member when the actuating member is in unlocked position, means for axially shifting the actuating member into locking and unlocked positions, a helical cam on one end of the actuating member and in association with one of the operating members, and a lock having a cylinder plug for engaging the helical cam and shifting the actuating member in one direction, said helical cam having a longitudinal passage for allowing the actuating member to be shifted axially in the same direction without the movement of said helical cam, said helical cam extending less than a complete circle to limit the circular movement of said cylinder plug.

15. In a door lock, a pair of spaced axially aligned plates, a pair of latch operating members mounted on said plates, a spindle mounted to rotate with both of the operating members, a bolt, a bolt actuating means mounted on the spindle, said means consisting of a hub and slotted arms extending in diametrically opposite directions therefrom, and a link connected to said bolt and extending into the slot of one of the arms, said means being constructed so that the link may be extended into the slot of the other arm when the bolt is positioned at the diametrically opposite side of said spindle.

16. In a door lock, a housing, a spindle rotatably mounted and axially reciprocable in the housing, a bolt reciprocally mounted at right angles to the spindle, means on the spindle for retracting the bolt and to allow free reciprocation of the bolt when the spindle is in an open position, stop means in connection with the bolt retracting means to prevent free reciprocation of the bolt when the spindle is axially shifted from said open to a locking position, a manual means

at one end of the spindle for positively manually forcing the spindle and the stop means from a locking to an open position, a latch for latching the spindle in said open position when said manual means is operated, and means at the opposite ends of the spindle for shifting the spindle in the same direction as the manual means.

17. In a door lock, a housing, a pair of knobs axially aligned with each other and rotatably mounted on the housing, a spindle axially aligned and rotatable with both knobs, but shiftable longitudinally with respect thereto, a bolt, means connecting the spindle to the bolt for causing retraction thereof when the spindle is in an unlocked position, stop means in connection with the spindle to prevent free reciprocation of the bolt, a spring for normally forcing the spindle into a locking position and for shifting the stop means into a position to prevent the reciprocation of the bolt, a manual means in one of said knobs for forcing the spindle against the action of the spring, a latch means for latching the spindle in the latter position, and means in the other knob for forcing the spindle in the same direction as said manual means.

18. In a door lock, a pair of spaced axially plates, a pair of door knobs axially aligned with each other and rotatably mounted on said plates, a spindle axially aligned and rotatable with both knobs, but shiftable longitudinally with respect thereto, a latch member, and means on the spindle for retracting the latch member.

19. In a door lock, a housing, a spindle rotatably mounted and axially reciprocable in the housing, a bolt reciprocally mounted at right angles to the spindle, means on the spindle for retracting the bolt and to allow free reciprocation of the bolt when the spindle is in unlocked position, a spring normally forcing the spindle into a locking position, a latch for latching the spindle in an unlocked position against the action of said spring, a pin and a notch means in connection with the spindle whereby the pin is forced into a notch of the notch means by the spring when released by the latch, said notch being so shaped as to allow rotation of the spindle in one direction, and another notch in connection with the former notch means for receiving the pin when the spindle is rotated in the latter direction for holding the spindle against rotation in latter direction.

HARRY E. FENDRING.
